UNITED STATES PATENT OFFICE.

NORMAN T. HALE, OF EUSTIS, NEBRASKA.

TIE-SLIP.

1,179,094.

Specification of Letters Patent.

Patented Apr. 11, 1916.

Application filed April 16, 1915. Serial No. 21,649.

To all whom it may concern:

Be it known that I, NORMAN T. HALE, a citizen of the United States, residing at Eustis, in the county of Frontier and State of Nebraska, have invented certain new and useful Improvements in Tie-Slips, of which the following is a specification.

The present invention relates to a tie slip, and has for its object to provide a device which can be applied to a four-in-hand tie before it is fitted within the collar and will prevent binding of the tie so that the knot can be readily slipped into proper position at the front of the collar after it has been tied.

Further objects of the invention are to provide a device of this character which is comparatively simple and inexpensive in its construction and can be readily manufactured from sheet material, which can be easily applied to the tie and will fit within the fold of a turn down collar without producing any bulging or distortion thereof, and which will operate in an effective manner to prevent binding of the necktie at the back of the collar so that the knot can be readily slipped in position after being tied.

With these and other objects in view, the invention consists in certain novel combinations and arrangements of the parts as will more fully appear as the description proceeds, the novel features thereof being pointed out in the appended claim.

For a full understanding of the invention, reference is to be had to the following description and accompanying drawing, in which:—

Figure 1 is a perspective view of a tie slip constructed in accordance with the invention, a necktie being shown as applied thereto in dotted lines. Fig. 2 is a transverse sectional view through the back portion of a collar, showing the manner of applying the tie slip to the collar. Fig. 3 is a transverse sectional view through one end of the tie slip showing the shoulders for holding the walls thereof apart. Fig. 4 is a view similar to Fig. 3 showing a modification of the invention.

Corresponding and like parts are referred to in the following description and indicated in all the views of the drawing by the same reference characters.

The tie slip may be inexpensively formed of any suitable sheet material, such as tin,

celluloid, or the like, and is designed to be applied to the middle portion of a four-in-hand tie so that it will be positioned at the back of a turn down collar and within the fold thereof when the tie is applied to the collar. The device includes a pair of opposed and slightly spaced walls 1 which are preferably similar in size and shape and are connected at their upper edges by an integral arched portion 1^a. The walls 1 are curved longitudinally to conform to the curvature of the collar and are of a sufficient width to receive the necktie between the same. As illustrated upon the drawing, the neck tie is designated by the reference character A, and the collar by the reference character B.

The lower edges of the walls 1 are provided at their middle portions with corresponding notches 2, said notches being of a sufficient size to provide ample clearance for the collar button so that the plates or walls 1 will not press the collar button inwardly and cause it to press uncomfortably against the back of the neck. The width of the walls 1 is slightly greater than the width of the contracted middle portion of a four-in-hand tie and the free edges thereof are extended inwardly toward each other to form corresponding shoulders 3 which form stop members and coöperate with each other to prevent the walls 1 from being pressed together in such a manner as to grip the necktie and interfere with the easy sliding thereof through the device. When placing the necktie in position or removing it therefrom the free edges of the walls 1 can be readily sprung apart, and after the device has been inserted within the fold of a turn down collar at the back thereof the stop shoulders 3 will prevent the walls 1 from being pressed together a sufficient amount to interfere with the sliding of the necktie. The notches 2 will also provide ample clearance for the collar button so that the device will not interfere in any manner with the operation of attaching the collar to the collar button. It has been found that substantially the only place a four-in-hand binds within a collar is at the rear thereof, so that when a comparatively short tie slip is fitted within the back of the collar in such a manner as to provide a channel within which the necktie can slide freely, no difficulty will be encountered in slipping the knot into proper position at the front of

the collar after it has been tied. Much annoyance is avoided by the use of a tie slip, and danger of tearing the necktie is eliminated.

5 A slight modification is shown by Fig. 4, in which the shoulders at the lower edges of the spaced walls 1 are provided by inwardly bent ribs 3^a, instead of being formed by returning the edges of the plates. These ribs 10 3^a coöperate with each other as in the previous instance to prevent the walls 1 from being pressed toward each other so as to grip the necktie. At the same time, the extreme edges of the plates 1 provide a 15 flared mouth which facilitates the placing of the necktie in position between the plates. It will be understood, of course, that the device is formed of resilient or spring material so that the walls or plates 1 can be 20 readily sprung apart when placing the necktie within the device or removing it therefrom.

Having thus described the invention, what I claim as new and desire to secure 25 by Letters Patent, is:—

As a new article of manufacture, the here-

in described guide for four-in-hand ties, including a short channel member formed of a single piece of sheet material which is bent to provide opposed side walls which are 30 similar in size and shape and connected along their upper longitudinal edges by a continuous arch, the lower edges of the plates being adapted to be sprung apart to admit of a necktie being readily inserted 35 between the same or removed therefrom, said free edges of the plates being provided at intermediate points in their lengths with corresponding notches which provide a clearance space for the collar button when 40 the device is inserted within the fold of a turn-down collar at the back thereof, and being returned to provide inwardly projecting opposed shoulders which coöperate with each other to prevent the plates from being 45 forced together to grip the necktie.

In testimony whereof I affix my signature in presence of two witnesses.

NORMAN T. HALE.
